[57] CLAIM

The ornamental design for a gastrostomy tube holder, as shown and described.

DESCRIPTION

FIG. 1 is a front perspective view of a gastrostomy tube holder, showing my new design, the broken line showing of the belt and pull tab is for illustrative purposes only and forms no part of the claimed design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a perspective view thereof, in open position;

FIG. 9 is a rear elevational view if a second embodiment of

the gastrostomy tube holder of FIG. 1, with the only differ-

ence residing in the appearance of a slot; and,

FIG. 10 is a perspective view thereof, in open position.
